MEANS FOR SIGNALING ON RAILWAYS

**Kenneth Alfred Fletcher, Seven Kings, England,
assignor to J. Burns Limited, Chadwell Heath,
England, a British company**

Application September 4, 1946, Serial No. 694,758
In Great Britain September 12, 1945

11 Claims. (Cl. 246—30)

1

This invention relates to means for signalling on railways and has for its object to permit signals being received on the train in fog and other atmospheric conditions when light and semaphore signals cannot be seen by the driver of the train, and also to permit the signalman to be advised of the presence of a train in his section during bad visibility. It does not however provide control over the character of the signal established by the operator, in response to traffic conditions in advance.

Signals are transmitted between the permanent way, e. g. from a signalling station (in this specification and claims, the term "signal station" or "signalling station" as applied to my system, refers to a box or station at which there is a signalman or attendant to supervise and control the traffic on the track) and the train, this being effected by means of electronic transmitting and receiving apparatus comprising an oscillator located both in or controlled by the signalling station and on the train, the oscillatory currents employed, which are preferably of a wave length of the order of 50 cm. to 5 m., being transmitted as electromagnetic waves between the permanent way and the moving train, e. g. the cab of the engine, by means of dipole aerials. The axes of the dipoles are arranged transversely to the direction of motion of the train. The oscillators serve both as transmitters and receivers, for which purpose they are each connected to an electronic or electromagnetic relay whereby the signals at the signalling station and in the cab of the train are set in accordance with the position of the train relatively to points on the permanent way, e. g. "Distant," "Home," "Clear." The signals set manually at the signalling station are thus exhibited both in the signalling station and in the cab of the train, where audible signals may be actuated, or the brakes of the train set in operation or the current to the motors of the train cut off. Furthermore, the presence of a train at the several signal points on the track can be indicated by appropriate signals in the signalling station.

The dipoles on the train are caused to radiate continuously, the corresponding oscillators being energized preferably by a battery on the train; the oscillators controlled by the signalling station are advantageously energized from the power line through a power pack.

If desired moreover, there are provided two "Home" signal points on the permanent way arranged at a suitable distance apart.

2

By this means, when a train passes the first "Home" signal point, an appropriate indication will be given in the cab. As the radiating dipole on the train approaches the radiating dipole at the second "Home" signal, the output from the oscillator acting as receiver in the cab will gradually increase until the field of maximum reception is reached. The gradual increase in output current may be measured on a milliammeter which is advantageously provided with a red coloured portion of its scale, so that when the pointer reaches such red portion, the driver will know that the train has reached the final part of the danger zone and will stop the train, not starting again until the "Clear" signal is given from the signalling station.

The oscillator circuit for standard gauge railways may be advantageously of the Colpitts type modified for ultra high frequency. As a different frequency is advantageously used for each of the signal points, the output to the dipole can be passed through a band pass filter to ensure that the desired frequency only shall be transmitted or received. The oscillator circuits may however be of the Barkhausen-Kurtz, linear or coaxial type, more especially with small gauge railways and electrically driven railways where the space between the conductor rail and one of the track rails is small.

30 The above mentioned relays actuated by the several oscillators may consist of mechanically operated relays or thyratron valves, the plate currents of which energize relay coils actuating relay tongues, may be employed. The various cancellations of lights and the automatic lighting of them are effected by interacting relays.

Each oscillator unit on the cab is advantageously built as a plug-in unit, and is fitted with a neon lamp in the anode circuit showing that the oscillator is functioning. Spares are carried, and, should the apparatus fail (the neon light consequently extinguishing), a new oscillator is plugged in.

45 In the signalling station there is fitted an illuminated map on which are arranged coloured lights showing the position of the signals and of the traffic. The switching on of a signal in the signalling station connects the anode of the valve to the supply, indicated through a neon lamp on the map. The filament is alight constantly. Whilst this imposes a shorter life on the valves, instantaneous operation is afforded together with instant indication of a failure.

50 By means of the invention the control of a train by signals from a signalling station is ren-

dered independent of fog, rain or other adverse atmospheric conditions and certainty of operation ensured since the signal given in the signalling station is repeated in the cab and the signalman is advised of the presence of a train in his section even when visibility is zero.

In the accompanying drawings, I have shown how my said invention may be conveniently and advantageously carried into practice, viz.:

Figure 1 is a diagram showing the general arrangement of the apparatus and circuits on the permanent way, and in the signalling station.

Figure 2 is a diagram showing the general arrangement of the apparatus and circuits on a train.

Figure 3 shows a track map provided in the signalling station.

Figure 4 shows a dipole antenna mounted beneath a vehicle of the train.

Figure 5 is a view of the arrangement of an oscillator unit with its corresponding power unit in position on the permanent way, while

Figure 6 is a diagrammatic view illustrating a train carried oscillator unit and its means of connection by plug connections.

Referring first to Figure 1, A represents the Distant dipole on the track B; C the first Home dipole; D the second Home dipole; and E the Clear dipole. F, G, G' and H are the oscillators corresponding respectively to the dipoles A, C, D and E; the two Home signal oscillators G and G' oscillating at the same frequency, and the Distant and Clear signal oscillators F and H oscillating at frequencies different from one another and from that of the Home signal oscillators. These three frequencies preferably lie within the range corresponding to wave lengths in the range of 50 to 500 cm., for example, the middle frequency, e. g. for the Home signals, may be 200 megacycles corresponding to a wave length of 150 cms. If desired these three frequencies may be stabilised by passing the oscillatory currents through corresponding filters J. Each of the oscillators is supplied with current through a power pack K fed from a power line L. The oscillators, when acting as receivers, actuate relays 17 at the signalling station through conductors M whereby electric lamps 19 at the signalling station may be energized (as hereinafter described).

Referring to Figure 2, Q, R, S are dipoles arranged beneath the cab on a train and connected respectively to oscillators T, U, V, these oscillators being tuned respectively to the Home, Distant and Clear frequencies, i. e. to the same frequencies as the track oscillators (G, G'), F and H respectively. The oscillators T, U, V are also, if necessary, provided with filters J between themselves and the dipoles Q, R, S. The oscillators T, U, V are also connected through relays W, X, Y to Home, Distant and Clear signals on a repeater panel I and are provided with suitable interlocking circuits as hereinafter described. In addition, the circuit of the Home signal relay coil W includes a milliamperemeter Z, the pointer of which is arranged to move from a zero corresponding to the value of the rest anode current of the Home signal oscillator T, e. g. 10 milliamperes, to higher values, e. g. 14 milliamperes, as the train moves towards a Home signal dipole. The Home oscillator T through its relay W may also be arranged to operate the brakes of the train by means of a relay 2. The oscillators T, U, V are energized from batteries 28 on the train through a common power pack 3.

Describing the apparatus now in more detail,

the circuits of the oscillators used on the train (Figure 2) and on the track (Figure 1) are each of the Colpitts type modified by the connection of the radio frequency choke to the centre of the inductance 5 connected in parallel with the series-connected condensers 6, 7 between which there is a connection to the cathode 8 of the triode 9; a tuning condenser 4 is also connected in parallel with the inductance 5. The filaments of the cathodes 8 are preferably heated directly from the battery 28 on the train. In the case of the oscillators on the track, the cathodes may be heated from the power packs K which may conveniently be housed in units 10 arranged beside the track, as illustrated in Figure 5, such units being connected to further track units 11 each housing the oscillator and dipole for the respective signal point, the dipoles being arranged transversely to the direction of motion of the trains. The arrangement of the dipoles below the train may be effected as shown in Figure 4, the connection between the oscillator T, U or V and the corresponding dipole being made by means of a coaxial feeder 12 having a suitable impedance.

The resistance of the grid leak resistor 91 of the train-carried oscillators is made such that when there is no coupling between train and track oscillators, only weak oscillation of the train-carried oscillators occurs. The value of the anode current under this condition is termed the rest anode current. When the dipoles of the train-carried oscillators pick up additional energy from the track oscillators, the anode current is increased. By reason also of the loose coupling obtained with the dipole aerials the anode current of the oscillating units will not be affected by the presence of unenergized oscillators on the track and the train-carried oscillators will act as super-regenerative receivers.

The oscillators of the signal dipoles A, C, D, E on the track are energized by closing their energizing circuits by means of interlocked switches 13 (Figure 1), whereby signal lights 14, consisting preferably of neon lamps shunted by resistances 15, are lighted and appear on the track map 16 (Figure 3) to indicate that the corresponding oscillator is in operation. The current in this circuit passes through the coil of the relay 17, the said coil being so wound that it does not move its tongue until additional energy is received from the corresponding track dipole when the dipole on the train is in close proximity thereto. The relay tongue then closes a circuit 18 including a signal light 19, which thus indicates the position of the train on the track map 16 (Figure 3). The switches 13 are interlocked by means of a bar 42 which is arranged so that the switches controlling the Distant and Home oscillators are automatically opened when the switch controlling the Clear signal oscillator is closed.

On the train, the actuating coils of the relays W, X, Y of the Home, Distant and Clear signals respectively, are each series connected in the anode circuit of the corresponding oscillator, a neon or other suitable indicating lamp 23, shunted by a resistor 24, being also arranged in series in said circuits in order to give a continuous indication that the respective oscillator is in operation.

These circuits are also interlocked in order to prevent the Distant and Home signals in the cab from being extinguished until the Clear signal switch has been operated at the signalling sta-

tion. The relay Y of the Clear signal has two relay tongues 25, 26, which are moved simultaneously when the relay coil is energized. When this relay is energized, the tongue 25 opens a circuit 27 including the battery 28, normally closed contacts controlled by the tongues 29, 30 of the relays X and W, and the Clear signal on the panel 1. The energization of the relay Y also causes the tongue 26 to open a circuit 31 including the actuating coils of the Distant and Home signal relays X and W and the anode circuits of the corresponding oscillators U and T. The tongues 25, 26 of the relay Y are returned to their circuit-closed position by a spring when the relay is de-energized to the extent that there is only the rest current of the oscillator V passing through its coil.

The relay X when energized from the dipole R, in addition to opening the contacts controlled by the tongue 29, actuates a further tongue 32 controlling a pair of normally open contacts in a circuit 33 which also includes the battery 28, the Distant signal on the panel 1 and a pair of normally closed contacts controlled by another tongue 34 of the Home signal relay W.

The relay W when energized, closes, by means of a tongue 35, a circuit 36 including the Home signal on the panel 1 and the battery 28, and a circuit 37 including the actuating coil of the brake operating relay 2 and the battery 28. Energization of the relay W also results in the opening of the pair of contacts previously described in the circuit 33 and controlled by the tongue 34, and in the opening of the contacts previously described in the circuit 27 and controlled by the tongue 30.

The relays X and W are constructed to retain their tongues in the attracted position by reason of the rest currents of the continuously energized oscillators U and T, when energy is no longer received from the corresponding oscillators F and G, G' on the track; although this is not the case with the relay Y, as aforesaid.

Figure 6 shows an oscillator unit T, U or V adapted to be connected to the dipole, battery and other circuits on the train by means of plug sockets 40, 41, a coaxial type plug 38 coupling the aerial Q, R or S at 40 and a multipin type plug 39 coupling the remaining connections at 41. The said plugs are arranged at the rear of the units and the sockets 40, 41 at the rear of the recesses in the cab designed to house the oscillator units.

The apparatus operates as follows:

Assuming that the section of the track in front of an advancing train is clear, the rest current of the oscillator V on the train controlling the Clear signal, e. g. a green light, will not energize its relay Y sufficiently to open the contacts at 25, 26, so that the circuit 27 controlling the green Clear signal lamp on the panel 1 is not broken and thus a green light is shown.

When the train reaches a section of the track controlled by a set of signals, and the way is not clear, the Distant signal oscillator F is operated from the signalling station and received by the cab through the oscillator U. The relay X is then energized, breaking the circuit 27 at 29, cancelling the green Clear light on the panel 1 and substituting the Distant red warning light therefor by closing the circuit 33 with the tongue 32.

When the first Home signal dipole C is reached, the oscillator T is energized (assuming the way still not to be clear for the train and the oscillators G and G' accordingly to have been energized), and the relay W is operated, the ammeter

Z simultaneously showing a high reading. Operation of the relay W opens the circuit 33 by means of the tongue 34 thereby cancelling the Distant light, and simultaneously closes the circuits 36 and 37 by means of the tongue 35. The circuit 36 lights up the Home signal on the panel 1, and the circuit 37 operates the brake controlling relay 2.

The second Home signal dipole is placed at such a distance down the track that the engine shall not overshoot it whilst its brakes are being applied. This signal is operated simultaneously with the first Home signal and its purpose is to allow the engine driver to creep forward until the ammeter Z which, after passing the first Home signal dipole has begun to fall, again rises and reaches a peak value as indicated by the upper coloured portion of its scale, i. e. when the train dipole Q and the track dipole D are a minimum distance apart. The relay W remains energized and the Home signal on the panel 1 therefore remains alight, since as stated above the relay W is retained by the rest current in the oscillator T. This creeping forward to the second Home dipole allows the engine to be in the best possible position to receive the Clear signal, the dipole E for which is placed within two feet approximately of the second Home signal dipole D. When the dipole E is caused to radiate by its corresponding switch 13 being closed, the Distant and first and second Home signals are automatically switched off by means of the interlocking bar 42 and their corresponding switches 13. The reception of this signal in the cab of the train energizes the relay Y which through its tongue 26 opens the circuit 31 through which the coils of the relays W and X are supplied. These relays are thus restored to their original positions the Home signal light being cancelled and the needle of the ammeter again falling. The green Clear light is reinstated when the relay Y is deenergized again, for which purpose the Clear signal current from the signalling station is only of short duration.

I claim:

1. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first

and second signalling devices at the signalling station.

2. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same respective frequencies, a dipole antenna having its axis arranged transversely to the direction of the track for each of said track oscillators, means controlled from the signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first and second signalling devices at the signalling station, wherein the oscillators are of a modified Colpitts type comprising a triode electron tube, a circuit comprising an inductance connected in parallel with a line consisting of two condensers arranged in series, a connection between the cathode of the triode electron tube and a point between said condensers, an auto-bias comprising a grid condenser and a grid leak resistor to the grid of said triode electron tube, a connection including the condenser of the auto-bias between the grid of the triode electron tube and one end of the said inductance, a connection between the plate of the said triode electron tube and the other end of said inductance, a tuning condenser connected in parallel with said inductance, and a radio frequency choke connected to a tapping point on said inductance.

3. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised

train-carried dipole to a track dipole, and electrical connections between the respective track oscillators and the corresponding first and second signalling devices at the signalling station, wherein the train-carried oscillators each comprise a grid leak resistor of such value that only weak oscillations normally occur, the value of the anode current under this condition being termed the rest anode current, and so that, if the dipole aerials of the train-carried oscillators pick up additional energy from the track oscillators the anode current is increased.

4. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first and second signalling devices at the signalling station, wherein on the train there is a Clear signal, a Distant signal and a Home signal, relays controlling the circuits of the Clear signal, the Distant signal and the Home signal respectively, series-connected contactors on each of the said relays, which contactors are closed when the relays are in their normal deenergised position so as to illuminate the Clear signal, a normally open contactor on the Distant signal relay, a normally closed contactor on the Home signal relay, connected in series with the last mentioned normally open contactor, which contactors serve to illuminate the Distant signal when the Distant relay is energised, a current meter connected in series with the coil of the Home signal relay, so as to indicate the degree of energisation thereof, a normally closed contactor on the Clear signal relay, which contactor is connected in series with the coil of the Home signal relay and in series with the coil of the Distant signal relay, so as to prevent energisation of the Distant and Home signal relays when the Clear signal relay is energised, a normally open contactor on the Home signal relay in series connection with the Home signal, adapted to illuminate said Home signal on energisation of the Home signal relay, and a source of electric energy connected to said signals and to said contactors.

5. Apparatus for signalling on railways comprising on the train a series of oscillators capable of radiating and receiving separate unmodulated electromagnetic waves of different radio frequencies, an antenna consisting of a dipole having

ing its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna arrangement including two home signal antennae spaced apart from each other and having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first and second signalling devices at the signalling station.

6. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, electrical connections between the respective track oscillators and the corresponding first and second signalling devices at the signalling station, said switches arranged at the signalling station and switches controlling the supply of energising current to each of said oscillators at the signal points on the track.

7. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequen-

cies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, electrical connections between the respective track oscillators and the corresponding first and second signalling devices at the signalling station, and a wave filter arranged in circuit with each of the dipoles on the track and on the train.

8. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first and second signalling devices at the signalling station, wherein on the train there is provided a signalling device, consisting of an electric lamp shunted by a resistor in the anode circuit of each oscillator.

9. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling sta-

tion adapted to be actuated by greater currents than such normal currents, which greater currents result from the proximity of an energised train-carried dipole to a track dipole, and electrical connections between the respective track oscillators and the corresponding first and second signalling devices at the signalling station, wherein the signalling devices at the signalling station adapted to be actuated by the normal operating currents in the energising circuits of the track oscillators, each consists of an electric lamp shunted by a resistor arranged in each said energising circuit.

10. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators; means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first and second signalling devices at the signalling station, wherein the signalling devices at the signalling station adapted to be actuated by greater currents than the normal operating currents in the energising circuits of the track oscillators, each comprises a relay arranged in each said energising circuit, which relay controls

a further circuit, including a source of electric energy and an electric lamp.

11. Apparatus for signalling on railways comprising on the train a series of oscillators capable of radiating and receiving separate unmodulated electromagnetic waves of different radio frequencies, an antenna consisting of a dipole having its axis arranged transversely to the direction of motion of the train for each of said oscillators, means for energising said oscillators, signalling devices on the train, relays connected in the anode circuits of said oscillators and controlling the circuits of said signalling devices; and on the track, an oscillator at each signal point corresponding to one of the oscillators on the train, the corresponding train and track oscillators operating at the same frequencies, a dipole antenna having its axis arranged transversely to the direction of the track for each of said track oscillators, means controlled from a signal station for energising said track oscillators, first signalling devices at said signalling station adapted to be actuated by the normal currents in the energising circuits of said track oscillators, second signalling devices at said signalling station adapted to be actuated by greater currents than such normal currents, which greater currents result from the proximity of an energised train-carried dipole to a track dipole, and electrical connections between the respective track oscillators and the corresponding first and second signalling devices at the signalling station, wherein the oscillators are made as units having connections brought to plug switches, whereby any oscillator may be readily replaced when necessary.
